UNITED STATES PATENT OFFICE.

AUGUST POMPEO, OF CORAOPOLIS, PENNSYLVANIA.

DESIGN FOR A POSTAL CARD.

49,620.

Specification for Design.

Patented Sept. 5, 1916.

Application filed July 11, 1916. Serial No. 108,752. Term of patent 14 years.

To all whom it may concern:

Be it known that I, AUGUST POMPEO, a citizen of the United States, residing at Coraopolis, in the county of Allegheny and State of Pennsylvania, have invented a new, original, and ornamental Design for Postal Cards, of which the following is a specification, reference being had to the accompanying drawing, forming a part thereof.

Copies of this patent may be obtained for five cents each, by addressing the "Commissioner of Patents, Washington, D. C."

The figure is a plan view of a postal card, showing my new design.

I claim:

The ornamental design for a postal card, as shown.

AUGUST POMPEO.
